UNITED STATES PATENT OFFICE.

ABRAHAM JACOB DYCK, OF DUNELM, SASKATCHEWAN, CANADA.

RAIL-JOINT.

1,291,803.

Specification of Letters Patent.

Patented Jan. 21, 1919.

Application filed May 20, 1918. Serial No. 235,579.

To all whom it may concern:

Be it known that I, ABRAHAM JACOB DYCK, a citizen of Canada, residing at Dunelm, in the Province of Saskatchewan, in the Dominion of Canada, have invented certain new and useful Improvements in Rail-Joints, of which the following is a specification.

This invention relates to improvements in rail joints and more particularly to that type of rail joint in which neither nuts nor bolts are employed. One object of the invention is to provide a rail joint that will prevent rail spreading as well as longitudinal creeping of the rails. A further object is to provide a joint that is simple in construction, of few parts, cheap to manufacture and efficient in operation. With the foregoing and other objects in view the invention consists in the combination and arrangement of parts to be hereinafter described, pointed out in the appended claims and illustrated in the accompanying drawings which form a part of this specification and in which—

Figure 1 is a plan view of my improved rail joint illustrating its application.

Fig. 2 is a side elevation of Fig. 1.

Fig. 3 is a longitudinal sectional view taken on line 3—3 of Fig. 1.

Fig. 4 is a cross section taken on line 4—4 of Fig. 1.

Fig. 5 is a cross section taken on line 5—5 of Fig. 1.

Fig. 6 is a perspective view of one plate employed.

Fig. 7 is a similar view of another plate employed.

Fig. 8 is a fragmentary view of a rail recessed terminally to receive one form of locking element I employ in a slightly modified form of the joint.

Fig. 9 is a longitudinal sectional view through the modified form of joint illustrating its application.

Fig. 10 is a perspective view of the form of plate used in the joint illustrated in Fig. 9.

Fig. 11 is a cross section through Fig. 9.

Like reference characters denote corresponding parts throughout the several views.

The reference numerals 1, 2 denote the meeting ends of two railway rails which are to be connected by my improved rail joint.

My rail joint comprises a major plate 3 and a minor plate 4, two minor plates being

used for each major plate employed. Each major plate comprises a base portion 5 one end of which terminates in the laterally extending wings 6 formed with the perforations 7 to receive the retaining spikes 8 that clamp the plate to the tie 9. The base portion 5 of the major plate extends beneath the railway rail upon the tie and is integral with the obliquely disposed lip flange 10 which is adapted for engagement with the flange of the rail, said lip flange 10 terminating in a vertically disposed supplementary flange 11. In the form of rail joint illustrated in Figs. 1 to 7 inclusive of the drawings the supplementary flange 11 is adapted for engagement with the fish plate 12 which lies flat against the web of the rail and is provided with the integral lugs 13 adapted for insertion in the web perforations 14. Coöoperating with the major plate 3 are the minor plates 4 each of which comprises a base portion 15 formed with the spike-receiving perforations 16 and adapted to be secured by spikes 8 to the tie 9. The base portion 15 is integral with the lip flange 17, obliquely disposed, which terminates in a vertically disposed supplementary flange 18 which, when the joint is assembled, engages with another fish plate 19 disposed flat against the web of the rail, the lip flange 17 engaging with the flange of the rail. The flange 11 of the major plate and the flange 18 of the minor plate are positioned upon opposite sides of the railway rail, one minor plate being disposed inwardly from each wing 6 of a major plate and spaced away slightly therefrom and spikes 8 driven between said members serve to secure them to the ties 9.

In Figs. 8, 9, 10 and 11 I illustrate a slightly modified form of rail joint in which very few parts are employed. I dispense entirely with the fish plates 12, 19 and instead of perforating the rail webs I form the rail web terminals with the recesses 20, which recesses are small at their mouths and relatively large at their inner terminations. When two rail ends come together the recesses in their webs register and form, substantially, a slot having enlarged ends and a contracted central portion. For engagement with the recessed rail portions 20 I provide the supplementary flange 11 of the major plate with a lug 21 having enlarged ends and a contracted central portion to correspond with the slot formed by the

alined recesses 20 in the rail-web ends. When this form of major plate is employed the supplementary flange 11 embraces the rail web and the enlarged ends of the lugs 21 being disposed in the ends of the said slots 5 longitudinal movement of the rails is prevented.

The spikes 8 driven between the wings 6 of the major plate and the adjacent minor plates are placed in position after the other spikes 8 have been driven to secure the plates to the tie. The spikes coming between the said wings 6 and the minor plates 10 drive or wedge said minor plates into engagement with the rail web and afford positive means of retaining the lugs 13 in engagement with the perforated portions 14 of the rail; said spikes, in other words, wedge between two movable parts to clamp 15 them upon the rail.

What is claimed is:—

1. In a rail joint, a major plate comprising a base portion terminating in laterally disposed wings, an obliquely disposed lip 25 flange integral with said base portion, a vertically disposed supplementary flange integral with said lip flange, a minor plate comprising a base portion, an obliquely disposed lip flange integral with said base portion, a vertically disposed supplementary 30 flange integral with said last named lip flange, fish plates adapted for engagement with said supplementary flanges and the web of the rail, and fastening means for said 35 major and minor plates.

2. In a rail joint, a major plate comprising a base portion disposed beneath the rail and terminating in laterally disposed wings, an obliquely disposed lip flange integral 40 with said base portion, a vertically disposed supplementary flange integral with said lip flange, minor plates comprising base portions disposed beneath the rail, one minor plate being disposed inwardly from each 45 lateral wing of said major plate, obliquely disposed lips formed integral with the base portions of said minor plates, vertically dis-

posed supplementary flanges integral with said lip flanges, fish plates adapted for engagement with said supplementary flanges and the web of the rail, and fastening means 50 for said major and minor plates.

3. In combination with the meeting ends of railway rails having alined recesses in their webs, the ends of said recesses being 55 enlarged, of a major plate comprising a base portion disposed beneath the rail and terminating in laterally disposed wings, an obliquely disposed lip flange integral with said base portion and adapted for engagement 60 with the rail flanges, a vertical supplementary flange integral with said lip flange for engagement with the rail web, terminally enlarged and centrally contracted 65 lugs integral with said supplementary flanges and adapted to register with the alined recesses in said rail webs, minor plates comprising base portions disposed beneath the rail, one minor plate being disposed inwardly from each lateral wing of 70 the major plate, obliquely disposed lips integral with the bases of said minor plates, and a supplemental flange terminating each of said last named lip flanges for engagement 75 with the rail web.

4. In a rail joint, a major plate, laterally disposed wings for said major plate, a minor plate disposed inwardly from each wing of each major plate, rail-end engaging means carried by said major plate, and means 80 adapted to wedge between said wings and the contiguous minor plates whereby said plates may be clamped against the rail ends, said rail-end engaging means being positively retained in operative relation.

In testimony that I claim the foregoing as my own I have hereto affixed my signature in the presence of two subscribing witnesses.

ABRAHAM JACOB DYCK.
